UNITED STATES PATENT OFFICE.

LEWIS B. CLARK, OF NEW HAVEN, CONNECTICUT.

TRACK-LAYER'S INSTRUMENT.

SPECIFICATION forming part of Letters Patent No. 688,826, dated December 17, 1901.

Application filed April 12, 1900. Serial No. 12,654. (No model.)

To all whom it may concern:

Be it known that I, LEWIS B. CLARK, a citizen of the United States, and a resident of the city and county of New Haven, State of Connecticut, have invented a new and useful 5 Track-Layer's Instrument; and I do hereby declare the following to be a full, clear, and exact description of the invention, such as will enable others skilled in the art to which it appertains to make and use the same.

Heretofore it has been customary for the engineer or track-layer in surfacing or alining his work to lie down on the surface of the road-bed and ascertain by his eye the 15 faults in the surface, alinement, or curves of the rails. By my invention the engineer or track-layer is enabled while in a standing position to better and more readily ascertain the differences in the surface and also by 20 changing its position the curving or alinement of the railway-track on which he is working and at the same time improve the character of the work done thereby.

In order that those skilled in the art to 25 which my invention appertains may more fully understand its construction and the methods of operating the same, I will describe the instrument, referring by letters to the accompanying drawings, forming a part of this 30 specification, in which—

Figure 1 is a perspective view of the instrument attached to a rail by means of the supporting-legs. Fig. 2 is a front and Fig. 3 an end elevation thereof. Figs. 4, 5, and 6 35 are glass plates, showing various arrangements of the lines upon their plane surfaces. Fig. 7 is a perspective view of the instrument attached to a rail by means of the overhanging shelf and retaining-clip. Fig. 8 is a longitudinal sectional elevation of the same. Fig. 9 is an end elevation, and Fig. 10 is a plan view thereof.

In the following description like letters of reference designate like parts in the several 45 figures.

Referring to the drawings, the letter A designates a hollow vertical case; B B, hollow horizontal cases projecting laterally from either side thereof and opening into said vertical case; C, a partition extending vertically 50 through the case A and dividing the same into two equal compartments and having a

hole a near the top thereof, which serves as a hand-grip for lifting and carrying the instrument, and D D railway-tracks, which are secured in the usual manner to cross-ties E E.

Within each of the cases B B are the mirrors F F, which lie at an angle of substantially forty-five degrees, resting at either end against the partition C and the bottom of the cases B B and upon which rest the glass squares L L, which are of substantially the same size and shape as the mirrors F F and having lines e e thereupon. These lines may be either vertical, horizontal, or curved, and in some cases I prefer to use a hair or thread placed upon the glass rather than to have the glass ruled in the usual way. The glass may be plain and without lines and a hair or thread substituted which can lie on the surface of the glass or be placed in the mouth or opening of the cases B B, as illustrated at f in Fig. 1.

Projecting laterally from one side of the instrument is a shelf G, which acts as a supporting means for the instrument when used for surfacing, and to prevent the same from being dislodged a spring-clip b is attached thereto and is sprung over the rail D, as shown in Figs. 1 and 3.

Vertically movable within guides K K, fixed to one side of the instrument, is an adjustable standard or slide H, which is retained in any of its adjusted positions by means of the thumb-screw c.

Pivotedly secured to the under side of the cases B B by the hinges g g are the legs or standards M M, which when opened are used to support the instrument upon the rail D when used for alinement or for adjusting curves. The legs M M when not in use are folded into the recesses O O and held therein by the buttons h h, the under surface of the cases B B and the legs M M being then substantially flush with each other.

When the instrument is placed upon the rails, as shown and described, the image thereof upon either side of the partition A is projected on the mirrors F F and the difference in alinement thereof, either to the right or left, will be easily and readily detected by means of the lines upon the glass plate L L, and for leveling and curving it is of course apparent that the same principle will apply.

either by using a horizontal or curved line upon the plates L.

I am aware that it is old to use a mirror for optical purposes, and therefore do not claim such construction broadly, but confine myself to the construction substantially herein shown and described.

Having described my invention, what I claim as new, and desire to secure by Letters Patent, is—

1. In a device of the character described, in combination with a case having two right-angled compartments therein located with the vertical portions thereof separated by a partition; of mirrors placed in the angles of said compartments against the said partition, the backs of said mirrors being toward each other; glass plates having a line upon their surfaces and adapted to lie upon the said mirrors; a supporting-shelf G; a spring-clip, b, for sup-

porting and holding the said device in operative position upon a car-rail; a vertically-adjustable standard H; and pivotally-hinged legs M M, substantially as set forth.

2. In a device of the character described, the combination with a case having a vertical portion A, horizontal portions B B, partition C, and shelf G having fixed thereto a spring-clip b; of an adjustable standard H; supporting-legs M M; mirrors F F; glass plates L L; and means attached to the end of the horizontal portions to serve as a guide-line in determining the alinement of the matter reflected in the mirrors, substantially as described.

This specification signed and witnessed this 23d day of August, A. D. 1899.

LEWIS B. CLARK.

In presence of—

ISAAC KOCH,

ARTHUR H. BOLTON.
